MECHANISM FOR PROTECTING BOILER FEED PUMP

Edward T. Dahl, Warwick Neck, R. I., assignor, by mesne assignments, to Reconstruction Finance Corporation, Boston, Mass., a corporation of the United States

Application September 22, 1951, Serial No. 247,783

3 Claims. (Cl. 103—42)

This invention relates to boiler feeds and more particularly to an arrangement for preventing injury to a main feed pump should the feed water to the boiler be throttled down to a point where the energy developed by the pump is not used in useful work.

The invention is particularly intended for a marine type of boiler feed system as distinguished from the systems sometimes used in large central control plants. In the use of a large central power plant, the loads which are carried by the plant are known from time to time or hour to hour and their variation is anticipated. No quick changes are involved. There is plenty of time for controls to be put into effect for the boiler feed water. Some elaborate electrical systems are utilized as a safety factor in case the loads vary beyond those anticipated and suddenly drop to a dangerous minimum. This occurs very infrequently, such as once or twice in five years.

On the other hand, in marine use the changes are sudden and cannot be anticipated by the operators of the engine room of a vessel, especially in cases where the vessel is coming slowing into a harbor and sudden changes of operating conditions are required. Especially does this occur in bringing the vessel to a dock. Conditions must always be ready for a full capacity load, while for a large part of the time the demand for boiler feed water is at a very minimum. Heretofore, it has been usual in the marine type of installation to provide a bleed from the main feed water supply back to the source of the water for the boiler in amounts of 15 per cent and sometimes as high as 25 per cent, which means a reduction in the efficiency which is very appreciable when a large amount of horse power is used. Where the boiler pump feeds are from pumps in the neighborhood of 500 horse power, there would be a loss at the 15 per cent level of bleed of 75 horse power, which is a considerable amount of loss resulting in inefficient operation.

This invention has to do with a system where the boiler feed water is supplied and in which there is a recirculation when the feed to the boiler approaches a dangerous minimum, while the recirculating portion of the system is entirely cut off with no recirculating permitted during the feeding of water to the boiler in amounts above a dangerous minimum for the pump to operate on.

One of the objects of the invention is to provide a system which will automatically cut in and cut out in response to a metering valve through which the water to the boiler passes.

Another object of the invention is to combine a metering valve and a check valve so that there will be no reverse flow permitted back to the pump in such situations as where several pumps are operating upon one line and one of the pumps may fail.

Another object of the invention is to provide a system which, should failures occur, will fail safe from the standpoint of liability of injury to any of the units of the system.

Another object of the invention is to provide a system in which the amount of flow of boiler feed water to the

2

boiler will be readily ascertained by looking at the metering valve.

Another object of the invention is to control the recirculating valve from a flow meter through a pilot valve which is directly responsive to the flow meter.

Another object of the invention is to provide a system in which the operation is in response to the variable area controlling the volume of flow as distinguished from variation of pressures.

10 Another object of the invention is to provide a control valve from the boiler feed water which will open slowly so as to prevent disruption of feed water controls.

Another object of the invention is to provide an arrangement in which there may be a plurality of units connected together with motion taken from one unit to operate another unit by transmitting motion from within the unit to outside the unit through suitable seals.

With these and other objects in view, the invention consists of certain novel features of construction, as will be more fully described and particularly pointed out in the appended claims.

In the accompanying drawings:

Figure 1 is a sectional view of a motor valve to be controlled;

25 Figure 2 is a sectional view of the control mechanism; Figure 3 is a sectional view of the valve plug on line 3—3 of Figure 2;

Figure 4 is a diagrammatic view of the system in which the control mechanism operates.

30 Referring to the schematic diagram, I have illustrated at 10 a boiler to be fed with water from a suitable source which, for purposes of illustration, may be a tank 11 which is provided with sort of a pre-heating mechanism for pre-heating the water supply. From this supply 11 a conduit

35 12 extends through a booster pump 13, thence through conduit 14 to the main feed pump 15. The discharge from this main feed pump is along the conduit 16 and through a spring-loaded flow-responsive metering check valve designated generally 17, and thence to the boiler

40 18 through conduit 19. This conduit is controlled by valve 19 which is so arranged that it opens as the demand for the boiler water increases or is closed down as the water supply becomes sufficient. Conduit 20 leads from the conduit 16 which extends between the pump and the

45 21 metering valve 17, back to the supply 11 with a motor-actuated control valve 21 interposed in this line which when open permits feed water to be transferred or recirculated back to the source 11, the amount transferred or recirculated being proportional to the amount that the valve 21 is open. In order that this valve 21 may be controlled as to its amount of opening, I have provided a pilot

50 valve 22 associated with the metering check valve 17 which is responsive in its action to the metering check valve so as to cause the valve 21 to be open or close more or less, dependent upon the position of the metering valve.

55 The control is exercised through some external power supply such, for instance, as water taken under pressure from the booster pump through the conduit 23 which leads to the pilot valve 22 and from the pilot valve is transferred through conduit 24 to the motor of valve 21.

60 The recirculating control valve designated generally 21 is shown in greater detail in Figure 1 and is a motor-actuated type valve in which the body is designated generally 30, having an inlet port at 31 and an outlet port at 32, which are placed in the flow line 20 of the system above described so as to convey liquid through the motor valve.

65 A valve seat is located at 33 along a conduit between the inlet and outlet ports. This valve seat occurs at a restricted portion of the passage from which there is a flare as at 34 connecting with the chamber 35. This passage is controlled by a valve plug 36 having a seating surface at 37 to engage the seat 33. This plug is tapered on a

somewhat sharper taper than the flare 34 and is provided with a plurality of grooves at 38 in order to better resist erosion. This valve plug is power operated and has a stem 39 screw threaded into the plug and extending upwardly therefrom to engage the button 40 on one side of the diaphragm 41 which is assembled with a button 42 on the other side of the diaphragm by means of a stud 43 having a flange 44 of a size to centralize a spring 45 and which is threaded as at 46 to receive nut 47 which through washer 48 binds the two buttons 40 and 42 on the diaphragm 41. An elastic stop nut 49 serves as a check to hold the parts in assembly.

The spring 45 which is centralized by the flange 44 engages the inner surface of a recess 50 on the upper portion of the body and serves to urge the valve plug upwardly off of its seat. A plug guide 51 is fitted within the body 30 to guide the plug in its reciprocable movement and extends into the bore 55 of the body and has a reduced end to engage a shoulder 56, while a stem guide is provided by a flanged nut 57 having a shoulder at 58 to engage a gasket 59 and having threaded engagement with the body as at 60. A seal 61 of polytetrafluoroethylene, usually referred to as "Teflon," engages the stem 39 and a boss of this stem guide 51 to serve as a seal against the escape of any fluid along the stem, thus leaving an isolated chamber 52 beneath the diaphragm 41. The chamber 53 above this diaphragm has an entrance port thereto at 54, which port is connected to the conduit 24 (Fig. 4) extending to the pilot mechanism associated with the metering check valve.

The metering check valve designated generally 17 in the diagrammatic showing of Figure 4 has an inlet port 70 (Fig. 2) connected to the conduit 16 and an outlet port to the boiler 71 connected to the conduit 18. The valve seat along the connection between the inlet and outlet port is designated 72 and a valve plug shaped as shown in Figures 2 and 3 is provided to control this conduit by providing a closure on the seat 72. This valve plug is designated generally 73 and comprises oppositely facing cups 74, 75 with a wall 76 between. The lower cup 75 serves as a guide to move along the surface 77 adjacent the seat and is provided with spaced passages 78, four in number equally distant about the skirt of the cup. These passages 78 serve to permit a restricted flow as the valve breaks off its seat and is partially opened. Projecting downwardly from this downwardly facing cup 75, the section of the plug is in the shape of a cross, as seen in the end view of this plug in Figure 3. This cross has radially extending fins 79 which also serve as guides engaging the surface 77 after the plug is opened so as to lift the skirt portion 75 clear above the seat and allow a substantially unrestricted flow through the spaces 80 between the cross-shaped section at the lower part of the plug. The upper cup 74 serves to receive the lower portion of a spring 81 which engages a button 82 which is shouldered as at 83 in the body of the casing and which spring acts downwardly upon a button 84 which presses upon the collar 85 fixed on the end portion of the stem 86, the end 87 of which presses upon the hardened insert 88 in the recess 89 in the central portion of the cap 74 of the plug 73 so as to urge this plug downwardly by the resilient action of the spring 81. This spring serves to always press the plug downwardly unless there is a pressure in the system sufficient to force the plug upwardly against the action of the spring, and thus the plug serves as a check valve as well as a metering valve, as will further be pointed out.

The button 84 has a cylindrical, tubular portion 90 extending upwardly from it which is guided internally by the guide member 91 which is threaded as at 92 onto the bonnet 93 which is shouldered as at 94 to engage a gasket 95 and which is drawn upwardly by the collar 96 threaded as at 97 to engage the upper end of this bonnet and is drawn upwardly by the screws 98 engaging the bottom of the recess 99 in the body of the housing. The stem 86

passes out through this bonnet 93 and is sealed as it passes through the guide 91 by means of a member 109 of polytetrafluoroethylene, known as "Teflon," so that no fluid will pass along the stem 86 and yet the stem will be free to move upwardly and downwardly in response to the movement of the valve plug. The stem passes through the space 101 and through the stem guide 102.

This stem 86 also serves as an indicator to denote the position or amount of opening of the valve and thus serves as a metering device. A pointer designated 105 is positioned on the stem 86 between two nuts 106 and 107 which may be adjusted along the threads 108 of the stem so as to adjustably position the pointer 105 as desired. A scale 109 may be placed at some convenient location for observation so that the position of the valve may be known, and this scale may be graduated as to the volume which is permitted to flow through the valve at different positions of the plug 73. The pressures are maintained within a short range so that the volumes may be graduated in this manner. The pressures also remain substantially constant so that the valve plug will be opened by the pressure in the system in accordance with the amount which may be supplied to the boiler by the regulation of the valve 19. Thus, the spring 81 will permit the plug to open or close in accordance with the demand required by the boiler.

In the event that the boiler needs a very small amount of water and the supply is approaching a dangerous minimum, this blow-responsive metering valve, just described, serves to actuate through the pilot valve mechanism 22, which is associated with the metering valve, the motor of control valve 21. The mechanism for accomplishing this will now be described.

There is provided a body or casing 110 which is bored to provide the passages and connecting passages which are required. A pilot valve moves in response to the metering valve in proportional amounts corresponding thereto so as to deliver liquid under pressure from some external source or some source other than the boiler feed water to the upper chamber 53 above the diaphragm of the motor (Fig. 1) so as to cause the control valve 21 to also move proportionately with respect to the metering valve. As indicated in the diagrammatic view, the source of supply is taken from between the booster pump 13 and the main feed pump 15 by a conduit 23, which conduit enters the casing 110 at 111 and flows along the bore 112, thence through the bore which forms conduit 113, thence through the bore forming conduit 114, through the bore forming conduit 115 to the bore 116, and thence to the outlet port 117 which joins the conduit 24 to the motor of control valve 21. Along this latter conduit there is a valve seat 118 and a valve plug 119 which has a long tapered surface which, as it moves upwardly, will further restrict the opening along the area adjacent the seat 118, while when the portion 120 of the plug engages the seat, the flow will be closed. The portion 121 of this plug below this seating part 120 is grooved as at 122, which will permit the portion of the flow which does not pass through the opening 117 to the motor of valve 21 to pass out through chamber 123 and bore forming conduit 124 to the drain port 125.

The stem 126 of plug 119 is threaded at its upper end 127 and provided with a cap screw 128 to which the lever 129 is connected through link 130. This lever 129 is pivoted as at 131 in a standard 132 extending upwardly from the casing 110 and extends over to the stem 86 where its bifurcated end 133 straddles the stem 86 and is in the path of movement of the nut 106 so that when the metering valve plug 73 approaches a dangerous minimum flow condition, this lever will be engaged and is moved upwardly at its point of connection with the pilot valve stem 126 so as to close off the pressure supply to the motor of valve 21 which has forced the valve 21 closed, thus permitting the spring 45 of valve 21 to open the valve in the amount permitted by

the relief of pressure in the chamber 53 above it. By this arrangement, should there be any failure of the pilot valve which controls the supply of pressure to the motor of control valve 21, the failure would permit the control valve to open and thus fail safe and prevent any harm occurring by reason of such failure to the main feed pump which this system is designed to protect.

As a safety in the system, a second complete shut-off valve is provided by there being formed a valve seat 140 along the conduit 112 and a valve plug 141 is provided with a beveled portion 142 which will engage this seat and shut off the supply of water or pressure to the motor of control valve 21. This plug also has a taper at 143 to engage a seat at 144 and normally is closed on this seat. A stem 145 extends upwardly from the plug 141 and is provided with a cap screw 146 which is connected to a lever 147 by a link 148. This lever 147 is pivoted at 147' and has a set screw 149 in it which is adjustable to engage the foot 150 attached to the lever 129 so that should it occur that the regulating pilot valve should fail at a point just before the metering valve closes, this shoe 150 would engage and move the lever 147 upwardly to draw the stem 145 upwardly and cause the valve plug 141 to engage seat 140 and close off the supply of pressure to the motor of control valve 21 so that as an additional safety, should there occur any failure in the mechanism of the pilot valve which controls the amount supplied to the motor valve, this mechanism would cause a safe failure.

Lever 129 is pulled downwardly against the stop to 30 keep valve plug 120 open by spring 135 and the lever 147 is held downwardly against the stop by spring 151.

The drain systems, above indicated, are for collection of the pure water and if not contaminated may be run back into the supply which goes to the tank 11; thus, any 35 drain for this pilot valve mechanism may be re-used if it appears to be non-contaminated. By the arrangement described, I am able to provide an automatic control for boiler feed water which will prevent burning up of the main feed pump should the supply to the boiler be reduced to such a minimum that the pump might otherwise become overheated or explode if its energy were 40

not absorbed such as by recirculation. The arrangement is hydraulic as distinguished from electrical and is adaptable for quick shifting of loads and long operation, it being known that electrical devices fail more frequently than the mechanical and hydraulic movements above described.

I claim:

1. In a boiler feed system having a supply reservoir, a boiler, a flow metering valve movable means coupled thereto, a pump for transferring water from the reservoir to the boiler through said valve, a by-pass conduit from the output of the pump to the reservoir, a normally closed control valve in said conduit having pressure responsive means coupled to said control valve, a second conduit from the output of the pump to said pressure responsive means, means in said second conduit coupled to the movable means of said metering valve for controlling the pressure in said second conduit whereby the total water output of said pump may be divided between the boiler and said by-pass conduit in accordance with the demand of said boiler.

2. A system as in claim 1 wherein said control valve is closed by the pressure responsive means and opened by spring means.

3. A system as in claim 1 wherein said control valve is closed by the pressure responsive means and opened by spring means, and wherein the means in said second conduit is an auxiliary valve which is closed by the movable means of the metering valve when the flow through the metering valve falls below a predetermined minimum thereby opening said control valve.
